RUFUS DUTTON, OF NEW YORK, N. Y.

Letters Patent No. 78,197, dated May 26, 1868.

IMPROVED METHOD OF CONSTRUCTING FINGER-BARS OF HARVESTERS.

The Schedule referred to in these Letters Patent and making part of the same.

TO ALL WHOM IT MAY CONCERN:

Be it known that I, RUFUS DUTTON, of the city of New York, in the county of New York, and State of New York, have invented a new and improved Mode or Method of Constructing the Finger-Bar of Mowing and Reaping-Machines; and I do hereby declare that the following is a full, clear, and exact description thereof, reference being had to the accompanying drawings, and to the letters of reference marked thereon, and making a part of this specification.

The nature or character of my invention or improvement consists—

Firstly, in forming, by suitable mechanism, a blank or plate, of metal, of a width sufficient for two finger-bars, having its edges raised or turned up, and having also two other raised or elevated ribs or parts, parallel to and each at such a distance from each edge of such plate, that when the plate is cut diagonally lengthwise through its central part, each part or half into which it is so cut will have its straight edge turned up or raised, and will also be raised or curved parallel to such front edge, and near to or towards the back side; and

Secondly, in forming a finger-bar, with two parallel ribs or raised portions, one at the front or straight edge, and the other near or toward the back side, whether such bar is made singly, or from a plate made wide enough for two bars, and afterwards cut in two parts.

Figure 1 is a section of a bar, having two raised ribs on it, and with the fingers attached to it.

Figure 2 is a cross-section of a plate formed to make two bars like that shown in fig. 1.

Figure 3 is a double plate, of reduced size, of which fig. 2 is a cross-section.

I consider it most preferable to first form a plate or blank of metal wide enough for two bars, and then cut it in two parts, as hereafter described. When this plan is adopted, a blank or plate of steel, or other metal, A B, is rolled out or formed, by suitable machinery or mechanism, of any thickness desired, and of a width sufficient for two finger-bars. Such plate is turned up or raised on each edge, a b, figs. 2, 3, and is also turned up or has a raised rib, c d, on each side of and towards the middle of the plate, parallel to the raised edges a b. Such ribs or raised parts c d are so located or placed with respect to the plate and its edges a b, that when such plate is cut diagonally lengthwise, on a line 1 2, fig. 3, each part or half of the plate will have one edge, its straight edge, raised or turned up, and will also have the rib or elevated portion, c or d, parallel to its front edge, and at or near the back side of the bar.

Fig. 2 represents a cross-section of a plate, formed to make two bars, and as it is before it is cut into two parts.

After the plate has been so formed, and has been made the length required for the finger-bar, it is cut or divided lengthwise, diagonally through its central portion, into two parts or halves, such diagonal line starting at one end of the plate, just behind one of the ribs or raised portions, c or d, and terminating at the other end of the plate, just behind the other inside rib or raised portion.

In figs. 1 and 2, the figures 1 2 indicate the starting and termination of such diagonal line. Each half of the plate, or each single bar A and B, has thus two raised or turned portions or ribs, one on the straight edge of each bar, and the other parallel to it, and near the back part of the bar, and also forming the edge of the bar at its narrowest end. At the widest end of the bar there will be, behind such back rib or elevated part, a flat portion of the bar, which gradually decreases in width, and terminating at the narrowest end. This flat part of the bar, behind the back rib, is shown in fig. 1.

A single bar, having such double ribs or raised portions, may be formed, by first rolling or forming a flat tapering plate, of steel or metal, the same as if for an ordinary flat bar, and then passing such plate between rolls, which shall depress the central portion, and form ribs or turned-up parts at each end of such rolls. The ribs on the bar being parallel to each other enable the plate to be treated and subjected to rolls as described.

Such double ribs materially strengthen the bar, and on both the front and back sides. Such double ribs may also be formed on a bar, whether one of such ribs forms the front edge of the finger-bar or otherwise.

What I claim as my invention, and desire to secure by Letters Patent, is—

Constructing the finger-bars of harvesters substantially as described, that is, forming a metallic plate of a breadth sufficient for two bars, such plate having its edges raised or turned up, and also having ribs or raised portions towards its centre, and parallel with its edges, so that when such plate is divided diagonally lengthwise, into two parts, it will form two bars, each having two parallel ribs or raised portions, substantially as set forth.

R. DUTTON.
